UNITED STATES PATENT OFFICE.

AARON P. STORRS, OF OWEGO, NEW YORK.

GAS-LIGHTER.

SPECIFICATION forming part of Letters Patent No. 723,331, dated March 24, 1903.

Application filed January 28, 1902. Serial No. 91,543. (No model.)

To all whom it may concern:

Be it known that I, AARON P. STORRS, a citizen of the United States, residing at Owego, in the county of Tioga and State of New York, have invented a certain new and useful Improvement in Gas-Lighters, of which the following is a description.

My invention relates to improvements in gas-lighters of the automatic type using a body of spongy platinum or other material which becomes incandescent when subjected to the reducing action of hydrogen.

The object of my invention is to provide novel means for sustaining the igniting-body and by which the latter after the gas has been ignited will be automatically removed from the heating effect of the flame, whereby its life will be greatly increased, and after the flame has been extinguished the igniting-body will return to its former position, so as to be again acted on when the gas is once more released.

To this end the invention consists, broadly, in combining mechanism with the support for the igniting-body so constructed and arranged that when subjected to the heat of the flame said mechanism will move the igniting-body or allow the latter to be moved—for instance, by gravity—out of the zone of objectionable heat, said mechanism being so arranged that when the influence of the heat is removed by the extinguishing of the flame its parts will return to their normal positions, thereby again moving the igniting-body or permitting the latter to be moved into the path of the gas ready for another operation. Preferably the elements of the device are so constructed and arranged that the igniting-body after it has performed its function will by the operation of the mechanism aforesaid be moved entirely outside of the chimney, so as to be thereby practically uninfluenced by the heat. When this is done, the igniting-body may be actually passed through an opening in the chimney, and the latter may therefore be conveniently of the mica type now extensively used in connection with incandescent gas-burners. When the chimney is provided with an opening through which the igniting-body passes, the support for the latter may carry a shield, which tends to close

said opening and keep it closed while the light is burning.

My invention also preferably provides means by which the position of the igniting-body relative to the burner can be readily and delicately adjusted and the adjustment changed should it be disturbed.

In the accompanying drawings I illustrate a convenient embodiment of the invention which has the advantages of simplicity, economy, and efficiency; but I do not wish to be confined to any details of construction, since obviously the broad invention can be carried out by widely different combinations of elements.

In the drawings which form a part of this specification, Figure 1 is a sectional view illustrating the upper portion of an incandescent gas-mantle and its support, showing a mica chimney surrounding the same and illustrating a perforated canopy, the latter carrying the thermostatic devices for operating the igniting-body; Fig. 2, a plan view of Fig. 1; Fig. 3, an enlarged sectional view of a suitable arrangement of parts for use in connection with an ordinary chimney, whether glass or mica; Fig. 4, a plan view of Fig. 3; Fig. 5, a section on the line 5 5 of Fig. 4, and Fig. 6 a section on the line 6 6 of Fig. 4.

In all of the above views corresponding parts are represented by the same numerals of reference.

In Fig. 1, I illustrate an ordinary incandescent mantle 1, carried by a support 2 and within which is located a Bunsen burner 3. Surrounding the mantle is a mica chimney 4, carrying a canopy 5, formed with a mica disk 6 at its top, all of the common and well-known construction. Secured to the under side of the mica disk 6 is a metal strip 7, formed with fingers 8, which guide a thermostatic bar 9 and permit the latter to expand or contract longitudinally. The thermostatic bar 9 is secured at one end to the mica disk 6 by a rivet 10. Secured between the thermostatic bar 9 and the strip 7 is a regulating-disk 11, eccentrically mounted on a rivet 12, passing through the mica disk 6. This rivet therefore holds both the regulating-disk 11 and the strip 7 in place on the mica disk, as will be understood. The regulating-disk 11 is mounted eccentric-

ally with respect to the rivet 12, as shown, and is provided with a series of openings 13, which may be engaged by a pin or other pointed instrument to turn the regulating-
 5 disk for the purpose of adjusting the position of the igniting-body, as will be explained. The mica disk 6 is formed with an opening 14, which discloses the edge of the regulating-
 10 disk and permits the latter to be adjusted.

10 The thermostatic bar 9 is provided with a slot 15 therein, and passing up through said slot is a light metal arm 16, which carries the igniting-body. The arm 16 is formed with cut-away portions 17, which are located in the
 15 slot 15, so that the arm 16 will be supported by the thermostatic bar 9 by the head-like portion 18 of said arm 16 above the cut-away portions 17. The edge of the regulating-disk 11 bears against the head 18, as shown, so that
 20 by turning the regulating-disk the angle of the arm 16 can be adjusted to normally swing its lower end over the burner 3, as shown in full lines in Fig. 1. This lower end of the arm is formed with an angular bend 19 and
 25 with a hook 20, as shown. The hook 20 carries the igniting-body 21, which is shown in the form of a small mantle and which is made of spongy platinum or other material capable of being brought to incandescence by the re-
 30 ducing action of hydrogen. Preferably, also, the hook 20 carries a disk or shield 22 for protecting the igniting-body when the latter has been automatically withdrawn from its normal position above the burner. Preferably
 35 the chimney 4 is formed with an opening 23 therein, having a protecting metallic rim 24 and so located that when the igniting-body is swung to one side, as shown in dotted lines, the latter will project through said opening,
 40 so as to be withdrawn entirely from the heat of the burner. In this position the shield 22 will rest on the inside of the chimney opposite the opening 23, so as to effectively close it, and thereby offer a further protection to
 45 the igniting-body.

I have referred to the disk 6 as being a mica disk, since ordinarily the canopies 5 are provided with disks of this kind at their upper end; but obviously a metallic disk may
 50 be used instead. When a mica disk is employed for this purpose, the thermostatic bar 9 is made of metal having a very much higher coefficient of expansion. I have experimented successfully with thermostatic bars made
 55 of brass and aluminium and find that the latter material is very desirable for the purpose, owing to its high coefficient of expansion. If the disk 6 is made of metal, then obviously the thermostatic bar 9 should be
 60 made of some other refractory material with a different coefficient of expansion.

Normally—that is to say, when the parts are in the position shown in full lines, Fig. 1—the arm 16 will occupy the inclined position shown, being sustained between the farther end of the slot 15 in the thermostatic bar and against the edge of the regulating-
 65 disk 11. In this condition it is assumed that the burner is not lighted. When the gas is turned on, it impinges against the igniting-
 70 body 21, which in a few seconds becomes sufficiently hot to ignite the gas. Immediately the heat of the flame causes the thermostatic bar 9 to expand, moving the far end of the slot 15 outwardly and permitting the arm 16
 75 to fall by gravity to the position shown in dotted lines in Fig. 1, the hook 20 passing through the opening 23 and carrying the igniting-body actually outside of the chimney. In this position the shield 22 will cover the
 80 opening 23, so as to further protect the igniting-body. When the gas is turned off, the thermostatic bar 9 will contract and the parts will return to the position shown in full lines in Fig. 1, the igniting-body being ready to
 85 again ignite the gas. Owing to the fact that the thermostatic bar works very closely below the regulating-disk 11, a very slight expansion or contraction of the former will result in a comparatively great movement of
 90 the lower end of the arm 16, whereby the igniting-body can be automatically removed from the effect of the heat by very simple mechanism.

In Figs. 3 and 4 I illustrate a slight modification of the device, which is adapted especially for use in connection with chimneys that are not provided with canopies. In this modification the thermostatic bar 9 is formed with a hook 25, which rests upon the chimney at one side, and the strip 7 is formed with a hook 26, resting upon the chimney at the other side. Instead of making use of a mica disk 6 I employ a mica strip 27, which at one end is anchored to the thermostatic bar 9 by
 100 a rivet 28 and at its other end is fastened by the rivet 12 to the regulating-disk 11 and strip 7. The strip 7 is provided with an opening 29, corresponding to the opening 14 in the mica disk 6 of Fig. 1 and which discloses the
 105 regulating-holes 13 in the disk 11. With this modification therefore it will be noted that the strip 7 is arranged above the mica body instead of beneath it, as with the arrangement shown in Figs. 1 and 2. In all other respects the construction of the modification shown in Figs. 3 and 4 and the operation of the same correspond with the construction and operation of the device shown in Figs. 1 and 2.

Having now described my invention, what I claim as new, and desire to secure by Letters Patent, is as follows:

1. The combination with a gas-burner, of an igniting-body normally located in the path of the gas, mechanism influenced by the heat of the burner for withdrawing said igniting-body out of the influence of the heat of the burner, and means for adjusting the position of the igniting-body toward and away from the path of the gas, substantially as and for the purposes set forth.
2. The combination with a gas-burner and a chimney surrounding the same and formed

with an opening therein, of an igniting-body normally arranged in the path of the gas, and mechanism influenced by the heat of the burner for moving the said igniting-body 5 through said opening, substantially as set forth.

3. The combination with a gas-burner and a chimney surrounding the same and formed with an opening therein, of an igniting-body 10 normally arranged in the path of the gas, a thermostat influenced by the heat of the burner for moving the said igniting-body through said opening, and a shield movable with the igniting-body for closing said opening when the igniting-body has been moved 15 through the same, substantially as set forth.

4. As a new article of manufacture, an attachment for chimneys of gas-burners, comprising mechanism influenced by heat and 20 having an arm for supporting an igniting-body, an igniting-body carried by said arm, and a shield carried by the arm adjacent to said igniting-body, substantially as set forth.

5. The combination with a gas-burner, of 25 two bodies having different coefficients of expansion and contraction, said bodies being secured together and extending parallel with each other, an arm supported by one of said bodies and engaged by the other, and an igniting-body carried by said arm, substantially as set forth.

6. As a new article of manufacture, an attachment for gas-burners, comprising a thermostatic bar, a regulating-disk, and an arm supported by said bar and engaged by said 35 disk, said arm carrying an igniting-body at its lower end, substantially as and for the purposes set forth.

7. As a new article of manufacture, an attachment for gas-burners, comprising a thermostatic bar, a regulating-disk, an arm supported by said bar and engaged by said disk, said arm carrying an igniting-body at its lower end, and a strip fixed to said regulating-disk and forming guides for said thermostatic bar, substantially as and for the purposes set forth. 40

8. The combination with the mica disk of a canopy for a gas-burner chimney, of a regulating-disk carried by said mica disk, a thermostatic bar secured to the mica disk below the regulating-disk, and an arm carried by said thermostatic bar and engaged by said regulating-disk, said arm carrying an igniting-body at its lower end, substantially as set 45 forth. 50

This specification signed and witnessed this 23d day of January, 1902.
